COATING MACHINE FOR COATING
FLEXIBLE SHEETS

William T. Snyder, South Lancaster, Mass.

Application September 22, 1948, Serial No. 50,537

2 Claims. (Cl. 118—11)

1

The present invention relates to improvements in coating machines, and more particularly to an apparatus for applying a liquid or semiliquid coating to a sheet material.

It is a primary object of the present invention to provide an improved means for applying a thin even coating of a liquid material to one or more surfaces of a substantially flat sheet, while the latter is being moved continuously, and without subjecting the sheet to any substantial flexure or bending.

A further object of the present invention is to provide such an apparatus which is not only efficient in operation, but which, at the same time, is adapted for high-speed operation.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings,

Fig. 1 represents a general perspective side view illustrating a coating apparatus in which the present invention is incorporated, and with one side frame portion of the apparatus removed so as to illustrate the various component parts of the invention more clearly.

Fig. 2 is a schematic drawing illustrating the manner in which a portion of the coating apparatus is actuated.

Fig. 3 represents a sectional view of a portion of the apparatus taken substantially along the line 3—3 of Fig. 1, and on an enlarged scale.

Fig. 4 represents a sectional view taken substantially along the line 4—4 of Fig. 3.

Fig. 5 represents a side view, on the same scale as Fig. 1, and illustrating a modified form of the present invention.

Fig. 6 is a fragmentary sectional view illustrating a further modification of the invention.

Referring particularly to Figs. 1 and 3, the machine in which the present invention is incorporated, comprises a pair of oppositely disposed machine frame elements 10 and 11, the bottom portions of which are adapted to be secured upon a floor. Carried between the frame elements 10 and 11, by any suitable means, such as rods 12, 12', is an open-bottom reservoir 12 which is adapted to contain a liquid coating medium C. Referring particularly to Fig. 1, it is to be understood that the reservoir 12 is fitted be-

tween a pair of cylinders 13 and 14 which are provided, respectively, with shafts 15 and 15' suitably journaled within the side frame members 10 and 11.

As will be hereinafter more fully described, the cylinders 13 and 14 are rotatably driven in opposite directions, as indicated by the arrows shown in Fig. 1. Furthermore, the cylinder 13 is rotated at a speed which is considerably less than the speed of the cylinder 14 so that the latter is adapted continuously to remove a thin even layer of the coating medium from the reservoir 12.

Also rotatably mounted between the side frame elements 10 and 11 is a coating cylinder or roll 16 which is provided with a supporting shaft 17. By referring particularly to Fig. 1, it is to be understood that the coating cylinder 16 is mounted in peripheral engagement with the cylinder 14, so that it will receive from the latter cylinder, an even layer of coating medium. In one form of the invention, the cylinders 13 and 14 are constructed of metallic material, while the coating cylinder is provided with a rubber covered surface.

Positioned between the side frame elements 10 and 11, and directly beneath and in parallelism with the coating cylinder 16, is an applicator roll, or cylinder, generally designated by the numeral 18. Disposed at the right-hand end portion of the above described machine, is an endless conveyor belt 19 which is trained over a pair of horizontally spaced conveyor rolls 20 and 21. The present invention contemplates the use of a conventional conveyor belt system, and thus it is sufficient to state that the rolls 20 and 21 may be suitably journaled between the side frame elements 10 and 11, and that any appropriate type of belt may be trained thereabout. Also, some form of driving mechanism, not herein shown, may be employed for driving the same in a manner such as to deliver sheet material from a supply source to the nip of the cylinders 16 and 18.

The present invention also contemplates the provision of a second conveyor belt 22 which is disposed at the left-hand side portion of the present machine, as viewed in Fig. 1. This conveyor belt 22 may be trained over several horizontally spaced rollers 23, only one of which is illustrated herein. Suitable mechanism, not herein shown, may be provided for driving this belt in a manner such that it may deliver sheet material from the nip of the cylinders 16 and 18 to any predetermined destination.

One method of actuating the above noted cyl-

inders 13, 14 and 16 is illustrated in Fig. 2. For example, the shaft 11 of the cylinder 16 may have provided on one end portion thereof, a gear 24 which is constantly rotated in a clockwise direction by means of an electric motor 25 through the medium of a set of reduction gears 26 and 27. The cylinder 14 is adapted to be driven from the cylinder shaft 11 through a gear train which comprises a pair of similar intermeshing idler gears 28 and 29. It is to be particularly noted that the gear 28 meshes directly with the gear 24, while the remaining idler gear 29 meshes directly with a driven gear 30 mounted directly upon the distal end portion of the cylinder shaft 15'. The idler gears 28 and 29 are of the same size, so that the cylinder 14 is driven at the same speed as the cylinder 16. It is to be also noted that the cylinder 13 may be driven from the cylinder shaft 15' through the medium of a pair of similar idler gears 31 and 32. The idler 31 meshes directly with the driven gear 30, while the idler 32 meshes with a large gear 33 carried upon the end portion of the shaft 15' provided on the cylinder 13. Due to the fact that the gear 33 is large compared with the gear 32, it follows that the cylinder 13 will be driven at a substantially slower speed than the cylinder 14. Thus, as hereinabove noted, this speed differential between the cylinders 13 and 14, will permit the latter cylinder to remove continuously and efficiently, a thin even layer of coating medium from the reservoir 12.

As will be hereinafter described, the applicator roll 18 is provided with a driving means which will function to rotate the roll in a counterclockwise direction. Thus, as the conveyor belt 19 delivers sheets of material, generally designated by the numerals 34, 34 to the nip of the cylinders 16 and 18, the latter elements will grip the sheets so as to deliver them to the upper surface of the conveyor belt 22. In so transferring the sheets from one conveyor belt to the other, it will be understood that the cylinder 16 will engage the top surface of each sheet as the sheet passes thereunder, so that an even layer of the coating medium will be applied to the sheet without substantial flexure or bending of the same.

As may be best understood by reference to Figs. 3 and 4, the applicator cylinder 18 is in the form of a thin cylindrical shell 35, the surface of which is provided with a plurality of small apertures or air ducts 36, 36. This shell 35 is fitted snugly about the outer periphery of a nonrotating hollow cylinder 37 which is provided at each end portion thereof with a ring of circumferentially spaced antifriction elements which, in a preferred embodiment of the invention, may take the form of bearing balls 38, 38. From this, it will be understood that the balls 38, 38 function as antifriction means which will permit the shell 35 to rotate freely about the element 37. Formed longitudinally across the upper surface of the element 37 is a slot 39, and communicating directly with the inner portion of the cylinder is a conduit 40 connected to a conventional type of vacuum pump, not herein shown. From this, it will be understood that as the shell 35 is rotated about the element 37, various of the shell apertures 36, 36 will be shifted into register with the slot 39 to the end that a continuous suction will be formed along the upper surface of the shell 35 and directly beneath the cylinder 16. Thus, if the shell 35 is continuously rotated at a speed in synchronism with that of the cylinder 16, the various sheets 34, 34 will be grasped be-

tween the nip of the cylinders 16 and 35, and the vacuum will tend to hold the underside of the sheet, as the latter is delivered in a left-hand direction, as viewed in Fig. 4. In other words, with the above described mechanism in operation, each sheet 34 will be moved by the right-hand conveyor toward the rolls 16 and 18 until its leading edge reaches that portion of the perforated shell or suction roll 35 which is connected to the source of suction through the slot 39. When this occurs, the sheet is carried into engagement with the under surface of the coating roll 16, which applies a thin even layer of the coating medium to the top surface of the sheet. As the coated portion of the sheet moves toward the second conveyor, the suction is released as the sheet passes the left-hand edge of the slot 39, as viewed in Fig. 4, and the weight of the sheet with the coating thereon is sufficient to cause the sheet to bend downwardly slightly until its leading edge reaches the second conveyor belt. After that, the following portion of the coated sheet passes readily onto the conveyor, which removes the sheet for drying the coating, or for the performance of any other desired operation.

In order to prevent a sheet from following downwardly around the surface of the shell 35, a stationary doctor blade 41 is provided which engages the surface of the shell 35 adjacent to the left-hand edge of the slot 39, as viewed in Fig. 4. This doctor blade 41 may be mounted upon a shaft 42 which, in turn, may be supported within the oppositely spaced frame elements 10 and 11.

As hereinabove noted, it is a primary object of the present invention to coat a sheet without appreciably bending the same. Thus, the suction roll 18 is particularly designed so as to prevent the leading edge portion of each section of sheet material from adhering to the periphery of the coating cylinder 16. Obviously, since the coating material normally used has somewhat of an adhesive characteristic, it will tend to make the leading edge of each sheet adhere to the surface of the cylinder 16, to the end that the sheet will wrap about the coating cylinder. However, by referring to Fig. 4 of the drawings, it will be understood that the slot 39 of the element 37 is wide enough so that the suction will strip the leading edge of each sheet away from the surface of the cylinder 16 as soon as the strip has emerged from the nip of the two cylinders 16 and 18. Heretofore, it was common practice to provide various types of unwieldy and inefficient mechanical elements for peeling the coated strips off of the coating roller. Clearly, such prior mechanical means were not only inefficient in operation, but they many times produced defects in the coated material. The present suction roll obviates such defects entirely.

In order to rotate the shell 35 in synchronism with the cylinder 16, there is provided about the left-hand end portion (as viewed in Fig. 3) of the shell, a ring gear 43. Meshing with this ring gear 43 is a pinion 44 carried upon the distal end of a shaft 45 which is driven by an electric motor 46. Referring particularly to Fig. 3, this electric motor 46 is carried upon a bracket 47 which in turn is rigidly secured upon the left-hand end portion of the element 37. Thus, rotation of the pinion 44 will drive the shell 35 in synchronism with the coating cylinder 16. Various well-known means may be employed for actuating the electric motors 25 and 46 in a proper speed ratio, so that the peripheral speeds

of the coating cylinder 16 and the shell 35 will be exactly in synchronism.

Referring particularly to Fig. 3, the entire roll assembly 18 is adapted to be yieldingly supported beneath the coating cylinder 16. In this connection, there is provided a base frame 48 which has threaded therein a pair of studs 49, 49. The upper portion of each of these studs 49 passes through an apertured trunnion 50 provided at each of the opposite end portions of the element 37. Coil springs 51, 51 surrounding the studs 49, 49 function to bias the roll assembly 18 toward the coating cylinder 16. Head portions 52, 52 of the studs 49, 49 function as stops which limit the uppermost position of the roll assembly. Provided on the lower threaded portions of the studs 49, 49 are lock nuts 53, 53 which function to prevent the studs from becoming loose in the base 48. By turning the heads 52, 52, the roll assembly may be adjusted with respect to the coating roll. Actually, the studs 49, 49 are so adjusted that the entire roll assembly 18 is positioned beneath the cylinder 16 so as to provide therebetween a space, the width of which is slightly less than the minimum width of any one of the sheets 34, 34. From this, it will be understood that the shell 35 will be continuously spring biased against the individual sheets 34, 34 as they pass between the nip of the coating cylinder 16 and the roll assembly 18. Also, this arrangement will insure that the shell 35 will never engage the periphery of the coating cylinder 16 and thus, none of the coating medium will ever be transferred to any portion of the roll assembly 18.

Also carried upon each of the studs is a nut 54 which engages the lower end of a coil spring so that by adjusting the nut along its stud, the biasing pressure between the rollers 16 and 18 may be varied.

From the foregoing, it is apparent that the above described mechanism is adapted to apply an even coating to the surface of a flat sheet, without subjecting the sheet to any substantial bending or flexure which would distort the sheet, or tend to curl it. By spring biasing the shell 35 toward the coating cylinder 16, there is insured an even application of coating, without any tendency to thin out the coating by the application of too much pressure as the sheet passes between the two cylinders. That is to say, by setting the distance between the cylinder 16 and the shell 35 to substantially the thickness of a sheet 34, the coating can be caused to flow readily onto the sheet from the coating cylinder 16. From this, it will be understood that the suction roll 18 actually functions to pull each sheet from the conveyor and toward the nip of the two rollers, with the coating roll merely following the movement of the sheet so as to apply an even coat of material upon the sheet's upper surface.

In the coating of certain types of sheets, I have found it to be desirable to reverse the direction of rotation of the coating roll 16 so as to produce a more uniform layer of coating medium upon the upper surface of such sheets. For example, by referring to Fig. 5, the coating roll 16 is made to rotate in a counterclockwise direction, the same as the lower roll or shell 35.

It is to be understood, however, that such rotation of the coating roll will not have an adverse effect upon the feeding action of the sheet material for, as hereinabove noted, the lower roll or shell 35 is entirely responsible for the feeding

action of the sheets, due to the fact that the sheet is forcibly biased against the periphery of the shell 35 by the suction action.

Whenever the coating roll 16 is rotated in a counterclockwise direction, the coating medium carried upon the periphery of the roll is applied upon the sheet material after the latter emerges from between the coating roll 16 and the applicator roll assembly 18, as represented by the rotatably driven shell 35. Thus, it will be understood that there will be no opportunity for the opposed surfaces of the rolls 16 and 18 to thin out the layer of coating medium which is applied upon the sheet. Furthermore, by referring to Fig. 5, it will be understood that with the coating roll 16 rotating in a counterclockwise direction, the coating medium will tend to accumulate slightly in an area designated by the reference character C' to the end that a uniform coating of the medium will be deposited over the upper surface of the sheet. Such an accumulation of coating medium insures that the entire surface of the sheet will be covered by a layer of optimum depth and of extremely uniform thickness throughout.

Referring now to Fig. 2, it is to be understood that whenever the coating roll 16 is to be rotated in a counterclockwise direction, the idler gears 28 and 29 are first removed from the driving mechanism and in lieu thereof, there is provided a single idler gear which is illustrated in dotted lines and designated by the numeral 55. Thus, the coating roll 16 may be readily rotated in a counterclockwise direction by substituting gear 55 for the idler gears 28 and 29, and thereafter reversing the direction of the motor 25. By so substituting the idler 55 for the two idlers 28 and 29, it will be manifest that the cylinders 13 and 14 will continue to rotate in the same direction as before, to the end that the coating medium will be properly removed from the reservoir 12 and applied to the surface of the coating roll 16.

With the coating roll 16 rotating in a counterclockwise direction, as described above with reference to Fig. 5, in some instances it may be desirable to delay the action of the applicator roll 18 in pressing a sheet 34 against the roll 16, until after the leading edge of the sheet to be coated has passed the lowermost point of tangency with the under surface of the coating roll 16. The purpose of such timing is to prevent the application of coating to the leading edge of the sheet, so that there will be an uncoated strip 75 along the edge of each sheet, as delivered by the operation of the machine.

One way of accomplishing this result is indicated in Fig. 5, wherein the entire applicator roll assembly is adapted to be maintained in a slightly retracted position in the interval between the departure of the trailing edge of a coated sheet and the arrival of the leading edge on an uncoated sheet, with reference to a fixed point slightly in advance of the lowermost point of tangency between a sheet and the under surface of the coating roll 16. To this end, the trunnions 50 of the roll assembly 18 are each mounted on a rod 56 surrounded by a spring 57 that normally serves to engage the trunnion 50 and yieldingly maintain it in a position determined by the engagement of a stop 58 on the rod with a frame member 59. With the stop 58 so engaged, the roll 18 will yieldingly press the upper side of a sheet 34 against the roll 16, as previously described.

Each rod 56 extends below its stop 58 and is surrounded by a solenoid 60 which, when energized, will serve to pull the rod and its associated trunnion 50 downwardly against the pressure of the spring 57, so that a sheet will not be held in contact with the coating roll 16 when the solenoid 60 is energized. One terminal of the solenoid 60 is connected to one of a pair of electrical supply mains 61, while the other solenoid terminal is adapted to be connected to the other supply main through the relatively movable contacts 62 and 63 of a relay, the operating winding 64 of which is adapted to be energized from a suitable photoelectric cell 65 located adjacent to the space between the rolls 16 and 18.

The photoelectric cell 65 is adapted to receive a beam of light as projected from a suitable lamp 66 located above the cell 65, with the light ray being indicated by a dot and dash line in Fig. 5. Therefore, as long as the cell 65 receives light from the lamp 66, the relay winding 64 will remain energized to hold the contacts 62 and 63 closed, as indicated in dotted lines, and thereby energize the solenoids 60, and exert a downward pull on the rods 56 which support the trunnions 50 of the roll assembly 18. However, when a sheet 34 is passing between the coating roll 16 and the applicator roll 18, as indicated in Fig. 5, the projection of the light ray to the cell 65 will be interrupted, thereby deenergizing the relay winding 64 and opening the circuit of the solenoid 60 at the relay contacts 62 and 63, as indicated in full lines in Fig. 5. Therefore, the solenoids 60 are deenergized during most of the time that the machine is in operation, so that the springs 57 are free to yieldingly urge the roll 18 in the direction of the roll 16, with the distance between the peripheries of the rolls being determined by the engagement of the stops 58 on the rods 56 with the frame member 59.

It is to be noted that the light ray, as projected by the lamp 66, is slightly offset from the lowermost point of tangency between a sheet 34 and the under surface of the coating roll 16. Therefore, when the trailing edge of the sheet shown as being coated in Fig. 5, clears the light ray, the resulting energization of the cell 65 will cause the relay contacts 62 and 63 to close, as indicated in dotted lines, with the resulting energization of the solenoids 60 causing the entire roll assembly 18 to be lowered slightly in advance of the arrival of the leading edge of the next uncoated sheet at the coating roll 16. Consequently, as the leading edge of the uncoated sheet arrives exactly beneath the coating roll 16, the applicator roll 18 will still be in a retracted position, and the leading edge of the sheet will not have any coating applied thereto, immediately.

However, as the leading edge of the sheet interrupts the projection of the light ray to the cell 65, shortly after the edge has passed the lowermost point of tangency with the roll 16, the resulting deenergization of solenoids 60 permits the springs 57, acting on the trunnions 50, to press the upper surface of the sheet into contact with the coated surface of the roll 16. As a result, sheets 34 passing between the rolls 16 and 18 with the arrangement shown in Fig. 5, will each have an uncoated strip along one edge, with the width of the uncoated strips being determined by the displacement between the projected light ray and the lowermost point of tangency on the under surface of the roll 16. Obviously, the above described arrangement for automatically retracting the applicator roll 18

during the intervals between the departure of a coated sheet and the arrival of an uncoated sheet, can be also applied to the mechanism shown in Fig. 1, wherein the rolls 16 and 18 are driven in opposite directions of rotation.

Referring now to Fig. 6, there is shown a further modification of the invention wherein the applicator roll 18, as represented by the perforated shell 35, is replaced by a conveyor belt 67 that is driven by suitable means not shown, so as to move continuously beneath the coating roll 16 in the direction of the arrow. The belt 67 provides perforations 68, and the lower surface of the belt is adapted to make close contact with the upwardly extending sides 69 of a suction box 70, with rollers 71 being adapted to support the belt along the sides 69. The suction box 70 is connected to a suitable source of suction, so that the belt 67 will tend to grip and hold sheets delivered to the belt for the purpose of having a coating applied thereto by the roll 16. The belt 67 is adapted to yieldingly maintain the upper surface of each sheet thereon in contact with the coating roll 16 through the action of a cylinder 72 located within the suction box 70, which cylinder 72 is mounted between trunnions 73 that are yieldingly urged in the direction of the belt 67 in substantially the same manner as shown in Fig. 3, with reference to the cylinder 37. With the modified arrangement shown in Fig. 6, it is obvious that the perforated belt 67 will function in substantially the same manner as the perforated shell 35, in causing the application of each sheet to the underside of the coating roll 16, without any possibility of the sheet tending to follow around the surface of the roll 16, due to adhesive action of the coating as it is applied to the sheet.

From the foregoing, it is apparent that by the present invention, there is provided an improved coating machine characterized by a number of advantageous features not possessed by existing machines of the rotating cylinder type. For example, the machine of the present invention is able to coat sheets of varying size and thickness without necessitating any changes in the mechanism in advance of running the different sheets, other than the previously described adjustment of the applicator member that determines the exact spacing between the moving surfaces of the roll 16 and either of the perforated applicator members 18 or 67. In this respect, the machine of the present invention differs radically from conventional coating machines of the type wherein the sheets to be coated are carried around the surface of a large cylinder, with each change in the size or thickness of the sheets to be handled requiring a different "make-ready." In the operation of the present machine, for a given setting of the applicator roll assembly, as determined by the stops 52, sheets of varying size and thickness within a considerable range can be run through the machine successively, due to the yieldable mounting of the entire assembly, which, however, is always set so that the applicator member, as represented by the perforated shell 35, or the perforated belt 67, never touches the coating roll 16 in the interval between the departure of a coated sheet and the arrival of an uncoated sheet at the point of tangency with the under surface of the roll 16.

I claim:

1. Apparatus for coating flexible sheets comprising in combination, a rotatably driven roll, means for supplying coating medium to the sur-

face of said roll, means for feeding a sheet in flat condition to engage one surface thereof with the periphery of said coating roll, means for supporting said sheet in a flat condition beyond said coating roll, a second roll having a perforated surface, a hollow casing for rotatably supporting said second roll and providing a port extending transversely to the direction of movement of a sheet and in communication with a portion of said perforated roll surface, means for rotatably driving said second roll around said casing, means for evacuating the interior of said casing to subject the uncoated side of a sheet to suction as it passes between said rolls within a zone defined by the limited number of perforations exposed to suction through said port, to thereby strip said sheet from said coating roll as it continues its movement in a flat condition onto said sheet supporting means, and means for yieldingly supporting said second roll, said evacuated casing, and said roll driving means, as a unit, so as to urge that portion of said roll in the vicinity of said port into engagement with the uncoated side of a sheet passing between the rolls.

2. Apparatus for coating flexible sheets comprising in combination, a rotatably driven roll, means for supplying coating medium to the surface of said roll, means for feeding a sheet in flat condition to engage one surface thereof with the periphery of said coating roll, means for supporting said sheet in a flat condition beyond said coating roll, a second roll having a perforated surface, a hollow casing for rotatably supporting said second roll and providing a port extending transversely to the direction of movement of a sheet and in communication with a portion of said perforated roll surface, means for rotatably driving said second roll around said casing,

means for evacuating the interior of said casing to subject the uncoated side of a sheet to suction as it passes between said rolls within a zone defined by the limited number of perforations exposed to suction through said port, to thereby strip said sheet from said coating roll as it continues its movement in a flat condition onto said sheet supporting means, means for yieldingly supporting said second roll, said evacuated casing, and said roll driving means, as a unit, so as to urge that portion of said roll in the vicinity of said port into engagement with the uncoated side of a sheet passing between the rolls, and means responsive to the passage of sheets between said rolls, for retracting said second roll in advance of the arrival of the leading edge of a sheet at said coating roll, and for releasing said retracting means to cause coating of said sheet at a predetermined distance from the uncoated leading edge thereof.
